SHOULDER MORTAR

Clarence E. Simpson, Springfield, Mass.

Application January 10, 1947, Serial No. 721,328

6 Claims. (Cl. 42—1)

(Granted under the act of March 3, 1883, as
amended April 30, 1928; 370 O. G. 757)

1

The invention described herein may be manufactured and used by or for the Government for governmental purposes without the payment of any royalty thereon.

This invention relates to a shoulder mortar, more particularly to means for absorbing the recoil forces of the mortar.

Many weapons adapted to be fired from the shoulder, particularly weapons firing a mortar projectile have exceedingly high recoil forces which are dissipated largely against the shoulder of the firer. Numerous devices have been resorted to with the view of reducing the recoil force to reasonable limits but have not been particularly effective. Nearly all of such devices so utilized employ only spring means but obviously such means is to a large extent entirely inadequate because of the tremendous recoil forces inherent in shoulder mortars.

Accordingly it is an object of this invention to provide an improved shoulder mortar wherein the recoil thereof is substantially reduced.

The specific nature of the invention as well as other objects and advantages thereof will clearly appear from a description of a preferred embodiment as shown in the accompanying drawings in which:

Fig. 1 is a fragmentary view of a shoulder mortar embodying this invention shown in longitudinal section with the hammer in the cocked or recoil position.

Fig. 2 is a view similar to Fig. 1 but showing the position of the barrel and hammer at the moment of discharge.

Briefly this invention consists of a shoulder mortar housing or receiver which contains a barrel mounted for limited longitudinal movement therein. A driving spring is contained within a tubular housing mounted in the rear of the receiver and is adapted to bear against the rear end portion of the firearm barrel to drive such forwardly after the compression of the recoil stroke. The firing pin is axially mounted in the breech end of the barrel and a hammer associated with the sliding barrel is arranged to strike the firing pin when such barrel is released by a trigger, hence discharge of the cartridge or shell is effected as the barrel is moving forwardly.

In Fig. 1 there is shown in assembled relation a firearm embodying this invention. Such firearm comprises mainly a cylindrical housing 15, a barrel 20 and a buffer mechanism 25. Cylindrical housing 15 is provided with threads 16 on the rear end thereof and an end cap 17 is screwed

2

therein. End cap 17 has an axial hole 18 and a threaded axial recess 19 is provided on the rear face thereof. A buffer tube 21 having a closed rear end is threaded into recess 19.

5 Barrel 20 is provided with a breech cap 22 which may be secured to the rear end of barrel 20 by threads or other means (not shown). Breech cap 22 slidably engages the interior wall surface of housing 15. A gland 23, preferably 10 secured to the forward end of housing 15 by threads 24, slidably supports the forward end of barrel 20 within housing 15. A cylindrical extension member 26 is secured to the rear end 15 the open rear end thereof is closed by a circular face of breech cap 22 preferably by brazing and 21 end plate 27. Such plate may be secured to 25 cylindrical extension member 26 forming a chamber 28 immediately in back of breech cap 22.

A rearwardly projecting axially disposed boss 20 29 is provided on plate 27 and a tube 30 is horizontally secured to such boss by threads 31, such tube being axially disposed within buffer tube 21. A spring guide 32 is provided within tube 30 and is suitably secured at the rear end in a 25 manner not shown. A spring 33 surrounds spring guide 32 and one end thereof abuts the closed rear end of buffer tube 21 while the other end of spring 33 abuts an integral flange 34 provided on the inside of tube 30 as shown in Figs. 1 and 2. 30 Spring 33 acts as a driving spring to force barrel 20 forwardly as well as to absorb the remaining recoil energy of the barrel in a manner to be later described.

An axial hole 35 is provided in breech cap 22 35 of suitable configuration to accommodate a firing pin 36. Firing pin 36 has a head portion 37 in the rear end thereof and a helical spring 38 surrounds firing pin 36, one end of such spring abutting head portion 37 while the other end 40 abuts a suitable shoulder provided in firing pin hole 35. Spring 38 retracts firing pin 36 in a well-known manner. A cap 39 is screwed onto a threaded boss 40 provided on the rear face of breech cap 22 to retain firing pin 36 within 45 hole 35.

A hammer 41 is pivotally mounted on a bracket 42 by a transverse pin 43. Bracket 42 is secured within chamber 28 as shown in Figs. 1 and 2, preferably by welding. A tang 44 integrally 50 formed with hammer 41 is provided therein for a purpose to be later described. Such tang is vertically disposed when hammer 41 lies in the horizontal position shown in Fig. 1. A longitudinally disposed slot 45 is provided in the bottom 55 tom of chamber 28 as shown in Fig. 1 to permit

tang 44 of hammer 41 to project therethrough.

A barrel release or trigger mechanism comprising a lever 46 and a sear 47 is mounted on the underside of housing 15 as shown in Figs. 1 and 2. Lever 46 is pivotally mounted by a transverse pin 48 in a bracket 49 which in turn is secured to the underside of housing 15 preferably by brazing or welding. A vertically disposed slot 50 is provided in lever 46 and sear 47 is vertically mounted therein by a transverse pin 51, such mounting permitting limited pivotal movement of sear 47. A slot 52 in the bottom of housing 15 permits sear 47 to project therethrough to engage a shoulder 53 provided on breech cap 22 to hold the barrel in the cocked position shown in Fig. 1.

A hammer tripping pawl 54 of lesser width than sear 47 is pivotally mounted on the underside of housing 15 somewhat ahead of such sear by a transverse pin 56 supported by a bracket 55. Pawl 54 is provided with a vertically disposed surface 57 which is arranged to engage tang 44 in a manner to be later described. A suitable spring 58 is placed about pin 56 to bias pawl 54 upwardly through a suitable slot 59 provided on the underside of housing 15 whereby surface 57 of such pawl lies in the path of hammer 41. A suitably curved arcuate surface 60 is provided on top of pawl 54 whereby such pawl may be cammed downwardly out of the path of hammer 41 on the recoil stroke of barrel 20. A slot 63 is provided in breech cap 22 enabling such cap to slide over pawl 54 on either the recoil or counter-recoil stroke without interference from such pawl. Since pawl 54 is of lesser width than sear 47, slot 63, which is slightly wider than pawl 54, will permit passage therethrough of pawl 54 but does not permit passage therethrough of sear 47, which is wider than slot 63, whereby sear 47 normally engages shoulder 53.

The mortar is readily cocked by forcing barrel 20 rearwardly against the bias of spring 33 whereupon such spring is compressed. The sloped surface 61 provided on the front upper corner of sear 47 permits such sear to be cammed downwardly as breech cap 22 passes over sear 47 whereupon torsion spring 62 raises lever 46 and sear 47 upwardly so that sear 47 engages shoulder 53 on breech cap 22 thereby securing barrel 20 in the cocked position shown in Fig. 1. A mortar projectile is then slid into position in barrel 20, the mortar now being cocked and ready to fire. Sear 47 is released by a downward push of lever 46 and barrel 20 with breech cap 22 and cylindrical extension member 26 moves forwardly due to the bias of spring 33.

Breech cap 22 passes over pawl 54, the slot 63 therein permitting such cap to clear pawl 54. When tang 44 of hammer 41 strikes surface 57 of pawl 54, such hammer is rotated in a clockwise direction as shown in Fig. 2, striking firing pin 36 thereby effecting discharge of the cartridge contained within barrel 20. If for some reason the cartridge fails to explode, barrel 20 will continue forwardly until the forward edge of breech cap 22 strikes the rear surface of gland 23 thus stopping barrel 20.

It will be apparent to those skilled in the art that before tang 44 strikes pawl 54, barrel 20 has attained considerable momentum. Therefore at the moment of discharge of the cartridge contained within barrel 20, such barrel has a substantial forward inertia to be overcome before recoil of such barrel can be effected. It is this inertia produced by setting the barrel in motion

before firing the cartridge which absorbs a substantial amount of the recoil energy developed by the explosion of the cartridge, thereby greatly lessening the remaining recoil forces to be absorbed by the buffer mechanism of the firearm.

It is desired to point out that the expanding brake shoes 64 as disclosed in my Patent No. 2,520,971 issued September 5, 1950 are utilized in conjunction with the device disclosed herein. Brake shoes 64 segmentally formed are slidably mounted in chordal slots 65 of cap 22 and are radially disposed to each other. Each shoe being provided with an outer arcuate surface complementary to the inner surface of housing 15 for cooperation therewith. The gas pressure developed in the housing by the explosion of the cartridge is transmitted to shoes 64 thereby forcing such shoes outwardly against the inner surface of housing 15. By means of such shoes, considerably greater recoil forces can be absorbed which means that a projectile having a much greater propellant force can be utilized as desired.

From the foregoing description it is apparent that the shoulder mortar disclosed herein is constructed to substantially reduce the recoil forces so that the residual recoil force can be readily absorbed by the conventional buffer mechanism of the firearm and the shoulder of the shooter without harmful effect to the shooter. It is further pointed out that the construction herein shown is simple and easy of operation and accordingly is inexpensive to manufacture. Such features are particularly desirable especially in times of war when mass production in large quantities are necessary.

I claim:

1. A firearm for discharging cartridges comprising a housing, a buffer member mounted on the rear of said housing, a barrel with a breech cap secured thereto slidably mounted within the housing, means for releasably holding said barrel in a retracted position, a firing pin mounted in said breech cap of said barrel, a hammer pivotally secured to said barrel, resilient means contained in said buffer member for urging said barrel forwardly upon release of said barrel holding means, and means engageable by said hammer as said barrel moves forwardly to rotate said hammer into engagement with said firing pin thereby effecting discharge of a cartridge while said barrel is in motion whereby a substantial amount of the recoil energy imparted to said barrel is absorbed in overcoming the inertia of said barrel.

2. In combination, a shoulder mortar having a tubular housing, a barrel slidably mounted in said housing for reciprocating movement, resilient means for urging said barrel forwardly, said barrel being provided with a rearwardly disposed hollow extension and having frictional means therein which is actuated outwardly against said tubular housing upon discharge of a shell, means for holding said extension in the cocked position, and means for discharging the shell after said barrel has been released from the cocked position and while said barrel is moving forwardly whereby said frictional means and the added inertia of said forwardly moving barrel absorb a substantial portion of the recoil energy imparted to said barrel.

3. In combination, a shoulder mortar having a tubular housing, a barrel slidably mounted in said housing for reciprocating movement, resilient means for urging said barrel forwardly, said barrel being provided with a rearwardly dis-

posed hollow extension and having frictional means radially disposed therein which is actuated outwardly against said tubular housing upon discharge of a shell, said extension being provided with a downwardly depending sear engaging shoulder, sear means mounted on said housing for engagement with said shoulder of said extension when said barrel is in the cocked position, and means for discharging the shell after said barrel has been released from the cocked position and while said barrel is moving forwardly whereby said frictional means and the added inertia of said forwardly moving barrel absorb a substantial portion of the recoil energy imparted to said barrel.

4. In combination, a shoulder mortar having a tubular housing, a barrel slidably mounted in said housing for reciprocating movement, resilient means for urging said barrel forwardly, a breech cap fixedly secured to said barrel, a plurality of brake shoes radially disposed and slidably mounted in said breech cap which are actuated outwardly against said tubular housing upon discharge of a shell, said breech cap being provided with a downwardly depending sear engaging shoulder and a rearwardly disposed hollow extension, said extension having a longitudinal slot therein, a hammer pivotally mounted within said extension, a lug on said hammer projecting downwardly through said slot, sear means mounted on the housing for engagement with said shoulder of said breech cap when said barrel is in the cocked position, and means pivotally mounted on said housing for engagement with said lug after release of said barrel whereby said hammer is rotated to effect discharge of a shell in said barrel after said barrel has moved a substantial distance forwardly and while said barrel is in motion and thereby cause the pressure of the gases to be partly expended upon said barrel and said brake shoes for resisting and arresting the forward movement of said barrel and the remaining pressure of the gases to return said barrel to the cocked position.

5. In a firearm having a housing, a barrel mounted for limited longitudinal movement therein, resilient means for urging said barrel forwardly, a breech cap fixedly secured to said barrel, said breech cap being provided with a downwardly depending rear engaging shoulder and a rearwardly disposed hollow extension, said extension having a longitudinal slot therein, a

hammer pivotally mounted within said extension, a lug on said hammer projecting downwardly through said slot, sear means mounted on the housing for engagement with said shoulder of said breech cap when said barrel is in the recoil position, and means pivotally mounted on the housing for engagement with said lug after the release of said barrel whereby said hammer is rotated to effect discharge of a cartridge in said barrel after said barrel has moved a substantial distance forwardly and while said barrel is in motion.

6. In a firearm having a housing, a barrel slidably mounted for longitudinal movement within said housing, resilient means for urging said barrel forwardly, means limiting the longitudinal movement thereof, said barrel having a rearwardly disposed hollow extension, said extension being provided with a longitudinal slot and a downwardly depending shoulder forwardly thereof, a hammer mounted in said extension, a lug on said hammer extending downwardly through said slot, sear means mounted on the housing for engagement with said shoulder of said extension in a recoil position, said resilient means being provided to drive said barrel forwardly upon the release of said sear means, and means projecting through the housing for engagement with said lug as said barrel passes over said last-mentioned means to rotate said hammer thereby discharging a cartridge in said barrel while said barrel is moved forwardly whereby a substantial reduction of the recoil force is obtained.

CLARENCE E. SIMPSON.
